IDLER PULLEY

Tommy H. Wherry, 104 Baylor,
Tyler, Tex. 75701

Filed Feb. 28, 1975, Ser. No. 553,876

Term of patent 14 years

Int. Cl. D12—05

U.S. Cl. D8—116

FIG. 1

FIG. 2

FIG. 3

FIG. 1 is a perspective view of an idler pulley in accordance with the design of the present invention;

FIG. 2 is an edge view of the idler pulley of FIG. 1 with the view being perpendicular to FIG. 3;

FIG. 3 is a face view of the idler pulley of FIG. 1. The front face and back face of the idler pulley of FIG. 1 are essentially identical and FIG. 3 is a view of either the front face or the back face.

I claim:

The ornamental design for an idler pulley, as shown and described.
